(57) **CLAIM**

The ornamental design for a bumper for bottle as shown and described.

DESCRIPTION

FIG. 1 is a top, front, right perspective view of a bumper for bottle showing our new design.

FIG. 2 is a bottom, rear, left perspective view thereof.

FIG. 3 is front view thereof.

FIG. 4 is a rear view thereof.

FIG. 5 is a top view thereof.

FIG. 6 is a bottom view thereof.

FIG. 7 is a left view thereof.

FIG. 8 is a right view thereof.

FIG. 9 is a top, front, right perspective view thereof, shown in an environmental use.

FIG. 10 is a top, front, right perspective view of another embodiment of a bumper for bottle showing our new design.

FIG. 11 is a bottom, rear, left perspective view thereof.

FIG. 12 is front view thereof.

FIG. 13 is a rear view thereof.

FIG. 14 is a top view thereof.

FIG. 15 is a bottom view thereof.

FIG. 16 is a left view thereof.

FIG. 17 is a right view thereof; and,

FIG. 18 is a top, front, right perspective view thereof, shown in an environmental use.

The broken lines in the figures illustrate portions of the bumper for bottle that form no part of the claimed design. Break lines having a jagged element illustrate that no particular length of the portion is claimed and form no part of the claimed design. The appearance of any portion between the break lines forms no part of the claimed design.

1 Claim, 18 Drawing Sheets
